Elihu Root

Seth P. Clark

The machine referred to in these Seth P. Clark was working, part of the machine containing a description of the method of the said Elihu Root himself of his improvement in the machine called a silk reel for drawing silk from cocoons.

The frame to which said reel is attached is composed of four parts of about ten feet in length formed into two plates about four feet in length with two parts of about ten feet in length which may be of just these sizes. I quote to one end of back frame a trough of about twenty inches in length as applied to the post and part.

The trough parts of about two inches in length frame into the two plates with a line wire through them with a transverse bar of about twenty two inches in length passing through which another with a transverse pulley about four inches diameter attached to the top of the transverse post with a pin and transverse guide made of brass or zinc bent in curved shape six inches in length with one end attached to a transverse pulley with a small screw into the other end fastened with a screw to transverse bar. The transverse bar about 4 feet wide in length fastened to said transverse bar about six inches apart - the bearing about 6 inches in length frame into the under side of said plates with a line of brass piping or such wire through the bearings with a small pulley attached to the end of said pipe about six inches with a pulley on each side about the middle of one of the bearings about 28 inches in the diameter the circumference of said pulley to be covered with list or brocatelle cloth. The reel post about 6 inches in length passes into the top of the plates. A reel shaft about 12 inches in length and the middle of which has a pin in each end of said shaft to turn on an intermediate part with a hole at one end of said reel shaft for a base and a party at the other end of said shaft about 12 inches in diameter the circumference of said pulley to be covered with list or brocatelle cloth when finished not over 15 inches in length and the base round about 10 inches in diameter and a shoulder on

69681

the end by the shaft with keys, in the other side of said shaft from the
head about 14 inches in length, so as to be in the axis of the head as and

the shaft. Up to about nine inches in length fastened
or framed to the plate on each side of the rear Relly with a Pin fasten
ed to the top of the shaft. Each the outer side of said Rely to be covered
with list a wooden Shutter of Tamarind-wood about 14 inches in length
to take or fit around the thickness of the plate about 1 inches from the
real part. It is about 2 feet in length with the end attached to the
Rely shaft with a pin through said lever which is made from the end made
part to be fulcrum that.

A trundle made fast to said frame by means of a cord
and the other end of said trundle made fast to the floor by a Hinge (The floor
must remain fixed) shaft may be extended from 4 feet to 20 or 30 feet in length
so as to extend to and from motion 234. or seven rods with the same power.

The reel may be put in motion either by hand, water, steam
or horse power applied to the cord so freely attached to the end of the line
shaft. The coconuts are to be placed in the trough and loaded on the reel with
hot water by means of a lead or iron pipe with one end placed in a Cauldron
or pot of boiling water the top of the pot or Cauldron made hot with a fire
and the other end of the pipe in the trough containing Coconuts, so heat will
steam and keep the Coconuts warm and fit for peeling and when the reel
is thus put in motion on the reel will go with great ease manage and turn
a deal. Whenever the operator wishes to return or stop the motion of the
reel it can be done by the foot before the trundle.

Then the reel is pulled with the hand must remain on
the reel till it is perfectly dry, thereby removing the two keys which pass
through the two side arms of the reel the arms will fall back on the
sides where may then be removed from the reel with ease and without
hurting. Dated 22nd day of December 1881. Slipknot known

as "Mitsupel"
